US00D897537S

(12) **United States Design Patent** (10) **Patent No.:** **US D897,537 S**
(45) **Date of Patent:** **** Sep. 29, 2020**

(54) **SURGICAL APPARATUS**

(71) Applicant: **Intuitive Surgical Operations, Inc.**,
Sunnyvale, CA (US)

(72) Inventors: **Timothy B. Hulford**, San Jose, CA
(US); **Robert B. Hubler**, Woodinville,
WA (US); **Nicholas W. Oakley**,
Portland, OR (US)

(73) Assignee: **INTUITIVE SURGICAL
OPERATIONS, INC.**, Sunnyvale, CA
(US)

(**) Term: **15 Years**

(21) Appl. No.: **29/648,161**

(22) Filed: **May 18, 2018**

(57) **CLAIM**

The ornamental design for a surgical apparatus, as shown and described.

DESCRIPTION

FIG. 1 is a perspective view of a surgical apparatus showing our new design in a first configuration;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof;

FIG. 7 is a bottom plan view thereof;

FIG. 8 is another perspective view thereof;

FIG. 9 is a perspective view of a surgical apparatus showing our new design in a second configuration;

FIG. 10 is a front elevational view thereof;

FIG. 11 is a rear elevational view thereof;

FIG. 12 is a right side elevational view thereof;

FIG. 13 is a left side elevational view thereof;

FIG. 14 is a top plan view thereof;

FIG. 15 is a bottom plan view thereof; and,

FIG. 16 is another perspective view thereof.

The broken lines depict portions of the surgical apparatus that form no part of the claimed design.

1 Claim, 16 Drawing Sheets
